UNITED STATES PATENT OFFICE.

NATHAN E. AYER, OF PORTLAND, OREGON.

CABLE-TRACTOR.

1,164,910.

Specification of Letters Patent. Patented Dec. 21, 1915.

Application filed October 18, 1915. Serial No. 56,569.

To all whom it may concern:

Be it known that I, NATHAN E. AYER, a citizen of the United States, residing in the city of Portland, county of Multnomah, and 5 State of Oregon, have invented certain new and useful Improvements in Cable-Tractors, of which the following is a specification.

My invention relates to cable tractors, and more particularly to a self-contained device 10 adapted to operate upon a supporting, or traction, cable and having such a propelling grip upon, or connection with, said cable, with means forming a part of said tractor and moving therewith for operating the 15 same, that it will carry a load along said cable and up a very steep incline, thus providing a device which will operate upon a cable stretched from a low to a high elevation, carrying its load up the incline without 20 any pulling attachments thereto from outside sources, other than the supporting cable upon which the device moves.

Among the salient objects of my invention are—to provide in a device of the character referred to, a plurality of pulleys adapted to run along a supporting cable, with means for holding the same in such adjusted relationships to each other relative to a supporting, or traction, cable that an 30 effective propelling grip upon, or connection with, said cable is had, with means for driving said pulleys, whereby to cause them to travel along said supporting cable; to provide in a device of the character referred to, 35 as one practical driving means therefor, a plurality of combination gear pulleys adapted to have intermeshing driving engagements with each other at their gear portions, and a traction engagement with the 40 supporting cable at their grooves; to provide in combination with a plurality of pulleys of the character referred to, means for driving all of said pulleys in unison, whereby to cause them to move upon the 45 supporting, or traction, cable, and in general, to provide an improved self-contained cable tractor of the character referred to, which is practical and efficient.

In order that others may understand my 50 invention, I have illustrated the same in the accompanying sheet of drawings which I will now describe.

Figure 1 is side elevation of one practical embodiment of my invention; and Fig. 2 is a top plan view showing the gear pulleys 55 and cable mechanism only.

Referring now to the drawings more in detail, my invention, as here illustrated, comprises a frame composed of two side members 1—1, having suspended thereto by 60 means of supporting bars 2—2, a platform 3, upon which is mounted a power furnishing mechanism, hereinafter again referred to. Mounted between the side members 1—1, near their tops, are two pulley gears 4—4, in 65 suitable journal boxes 5—5, movably mounted and adjustable, in opposite direction, on an arc by means of adjusting screws 6—6. Also journaled between said side members 1—1, is a third pulley gear 7. Said 70 pulley gears, it will be noted by reference to Fig. 2, have circumferential cable grooves around their middle portions and gears at opposite sides thereof. A supporting, or traction, cable 8, passes under the pulleys 75 4—4, in their grooves, and over the pulley gear 7, in the manner indicated, said pulley gears being so positioned relative to each other that their gear portions are in mesh with each other and their grooves are in 80 register with each other. The pulley gears 4—4, with their bearings, 5—5, as stated, are adjustable on the arc of a circle concentric with the axis of the pulley gear 7, whereby as said gears 4—4, are moved 85 downwardly around the gear 7, an increase in the wave-like bend, or kink, of the supporting cable 8, is made. This kink, or bend, in the cable 8, makes possible the necessary grip of the pulley gears upon, or 90 connection with, said cable, whereby said tractor can be propelled along said cable, even when it is stretched on an incline, making it possible for said tractor to overcome 95 the action of gravity thereon.

As one means for driving said pulley gears 4—4 and 7, I have provided a small gear 9, mounted between the frame members 1—1, and adapted to mesh with the gear portion of the pulley gear 7, said gear 9, 100 being driven through a sprocket wheel 10, a sprocket chain 11, and a sprocket wheel 12, shown behind and adapted to be driven from a gear 13, which is adapted to be

driven by one or the other of two beveled gears 14 and 15, mounted upon the engine shaft 16, and controlled by a clutch mechanism 16', of any suitable type. The engine shaft 16 is provided with the usual shift gear mechanism in a gear box, as at 17, and is also provided with a pinion 18, which is directly behind a gear 19, mounted upon a shaft 20, which is parallel with the engine shaft 16, the shaft 20 being driven from the engine shaft 16, through said pinion 18 and gear 19. The shaft 20 is provided with a worm, 21, for driving a drum 22, upon which is wound a lifting cable 23, which extends downwardly and around a block 24, having a hook 25, and thence upwardly to a point where it is attached to the frame members 1-1, as at 26. The engine or motor is designated as 27, and may be of any desired type. The shaft 20 and its gear 19, may be connected into and out of driving relationship with the engine shaft 16, by means of any suitable clutch mechanism, designated 28. Said cable 23, is designed for lifting the weight, or load, to be carried, from its location up to the cable tractor, and then holding the same as the cable tractor is driven along said cable to the place of discharging said load.

30 Thus I have provided a self-contained cable tractor adapted to have a traction connection with a supporting cable by means of the association of the pulley gears relative to each other and to the supporting cable which is stretched from one point to another.

35 The main feature, and that which constitutes the invention of this application, is to be found in the provision of three cable pulleys associated with each other and with a supporting or traction cable in such a way as to produce a traveling wave-like action, in said cable, through said pulleys, with means for driving said pulleys in the proper direction to cause them to advance along said cable in one direction or the other, all of said pulleys having direct engagement with said cable and preferably being of the same size and driven at the same speed. By reason of this particular association of traction 40 pulleys upon a supporting, or traction, cable, with means for varying the positions of said traction pulleys relative to each other and so as to increase the wave-like bend, or kink, in said traction cable, a holding grip on said cable is secured which is sufficient to carry my cable tractor along said cable even at a steep incline, thus making the device particularly adapted for lifting logs out of a river, or from a low elevation, and carrying them up a stretched cable to a higher elevation, or other place of discharge.

45 I am aware that many changes can be made in the embodiment of the invention as here shown for purposes of illustration, without departing from the spirit thereof,

and I do not, therefore, limit my invention, except as I may be limited by the hereto appended claims.

I claim:

1. In a cable tractor, the combination with a supporting, or traction cable, three traction pulleys arranged two on one side of said cable and the other therebetween, at the opposite side of said cable, with their peripheries, or cable grooves, in overlapping relationship in the same plane, whereby to produce a kink, or wave-like bend in said supporting, or traction cable, and means carried by said tractor for driving said tractor pulleys in unison, whereby to cause them to advance upon said supporting, or traction cable.

2. A cable tractor of the character referred to, comprising in combination with a supporting, or traction, cable, a frame, three tractor pulleys mounted therein in the same plane, two of said pulleys being mounted at one side of said cable at a space apart, and the other of said pulleys being mounted therebetween at the opposite sides of said cable and in partially overlapping relationship with said two pulleys, whereby to cause a kink, or wave-like bend in said cable, and means provided in said frame with driving connections therefrom for driving said traction pulleys, whereby to cause them to move along upon said cable.

3. In a device of the character referred to, in combination with a supporting, or traction, cable, three combination gear pulleys, arranged two at one side of said cable and the other therebetween at the opposite side of said cable, in the same plane, said gear pulleys having grooves to receive said cable and having gear portions adapted to mesh with each other, and means for driving said gear pulleys one from the other, whereby to cause them to move along upon said traction cable.

4. A cable tractor of the character referred to, comprising in combination with a stretched supporting cable, a frame, three cable pulleys adapted to said cable and each provided with means for driving it, said cable pulleys being arranged in the same plane, two at one side of said cable and the other at the opposite side thereof and in overlapping, or staggered, relationship between the two, whereby to cause a kink, or wave-like bend in said cable, and power mechanism with driving connections to said pulleys for driving the same together, whereby to cause said cable tractor to move along said supporting cable.

5. A self-contained cable tractor of the character referred to, comprising in combination with a stretched supporting cable, a frame, three cable pulleys mounted therein, in the same plane, and in overlapping, or staggered, relationship with each other, with

- said supporting cable passing therebetween through a wave-like path, power furnishing means carried by said tractor, driving connections therefrom to one of said pulleys, 5 and driving connections from said pulley to the other pulleys, whereby said pulleys are all driven together in a direction to cause them to move along said cable, substantially as described.
- 10 6. In a device of the character described, in combination with a supporting cable, a plurality of combination gear pulleys, each having a groove adapted to said cable and each having a gear portion adapted to mesh 15 with the gear portion of another, and means for driving said gear pulleys.
- 20 7. In a cable tractor, in combination with a stretched supporting cable, a plurality of combination gear pulleys arranged in the same plane at opposite sides of said cable, each of said gear pulleys having a groove to receive said cable, and each of said pulleys also having a gear portion at the side of said 25 groove and adapted to mesh with the gear portion of another of said gear pulleys, and means for driving one of said gear pulleys, whereby to drive the others therefrom.
- 30 8. In combination with a stretched supporting cable, a frame, three combination gear pulleys mounted in the same plane in said frame, two at one side and one therebetween at the other side of said cable in overlapping, or staggered relationship with each other, whereby to cause a kink, or wave-like bend in said cable, each of said gear pulleys having a groove adapted to receive said cable and each of said pulleys having a gear

portion at the side of its groove, the gear portion of the pulley between the other gear pulleys, and on the opposite side of said cable, being in mesh with the gear portions of both of the other pulleys on the opposite side of the cable passing therebetween, power furnishing mechanism, a hoisting

drum with lifting cable and block adapted 45 to be operated thereby, and driving connections from said power furnishing mechanism to said gear pulleys, and to said hoisting drum, substantially as described.

9. A self-contained cable tractor of the 50 character referred to, comprising in combination with a stretched supporting cable, a frame, three cable pulleys mounted therein, in the same plane, and in overlapping, or staggered, relationship with each other, with 55 said supporting cable passing therebetween through a wave-like path, power furnishing means carried by said tractor, driving connections therefrom to one of said pulleys, driving connections from said pulley to the 60 other pulleys, whereby said pulleys are all driven together in a direction to cause them to move along said cable, a hoisting drum with lifting cable and block adapted to be 65 operated thereby, and driving connections from said power furnishing means to said cable pulleys, and to said hoisting drum, substantially as described.

Signed at Portland, Multnomah county, Oregon, this 12th day of October, 1915.

NATHAN E. AYER.
